UNITED STATES PATENT OFFICE.

CHARLES ROANE ELLIOTT, OF RICHMOND, VIRGINIA.

BUILDING CONSTRUCTION.

SPECIFICATION forming part of Letters Patent No. 779,268, dated January 3, 1905.

Application filed April 27, 1904. Serial No. 205,239.

To all whom it may concern:

Be it known that I, CHARLES ROANE ELLIOTT, a citizen of the United States, residing at Richmond, in the county of Henrico and State of Virginia, have invented new and useful Improvements in Building Construction, of which the following is a specification.

My invention relates to improvements in building construction, and the object is to 10 simplify and improve the existing art in that branch or class embodying the adaptation and securing of tiling or similar protective facings to either exterior or interior walls, or to floors or ceilings, or to horizontal or to vertical 15 surfaces, wherever such protection may be desired or required.

The invention embodies tiles or plates of any suitable style or make and hangers or supports of novel make to hold and support 20 the facing in position relatively to the surface to be protected or ornamented.

The invention further consists in the novel construction of parts and their novel aggroupment in operative combination, as will be hereinafter fully specified, and the asserted novelty particularly pointed out and distinctly claimed.

I have fully and clearly illustrated my improvements in the accompanying drawings, to be taken as a part of this specification, and 30 wherein—

Figure 1 is a perspective view of a wall to which my improved facings are applied and showing the supporting-stirrups in position and also the interengagement of the tile-hangers with the stirrups. Fig. 2 is a perspective view showing the approved way of attaching the tile-hangers to an old wall, the tiles or facings being positioned closely adjacent to the face of the old wall. Fig. 3 is a similar 35 view wherein the hangers are formed with spacing-pieces to hold the tile-wall spaced from the main wall. Fig. 4 is a detail vertical cross-section showing the manner of fastening the stirrups in the masonry and the tile-wall to the hangers. Fig. 5 is a form of hanger suitable for supporting the tile-wall. Fig. 6 is a form of hanger adapted for use in instances indicated in Figs. 2 and 3. Fig. 7 indicates the 40 application of the improvements to weather-boards. Fig. 8 indicates the application 45

to studdings. Fig. 9 indicates the attachment to studdings and spaced away from them to create air-spaces between the studding and the inner face of the tiling. Fig. 10 shows the improvements as applied to form protection to wooden studding and make a flue. Fig. 11 is a view, partly in vertical section, showing the union of the tiles and the manner of securing the bottom or base-line to the structure.

In the drawings similar parts appearing in the several illustrations are designated by the same reference notations.

It may be premised the improvements may consist so far as the material is concerned of any suitable articles, such as plates in the order of press-brick plates, tile, terra-cotta, cement blocks, marble, or stone facings, and may be of any interfitting contour desired. The sections or blocks of the facings may be of any size and have their faces plain or ornamented with any designs selected. They may be of the original color of the material or they may be colored to suit the whims or desires of the mind. It may be further premised that the 75 improvements may be utilized for the various purposes of the trade wherever the facings are applicable, such as facings for old or new brick walls, weather-boardings, for flooring, base-boards or wainscoting, hollow walls and partitions, damp-proofing, and for hot or cold air flues, or for flues or inclosures for pipes, tubes, or wires.

Referring to the drawings, A designates a wall of any of the usual constructions. In 85 the wall A at stated intervals are secured staples or stirrups 1, having their inner ends turned down and extending into the dividing-line between the bricks and their outer ends turned to lie closely adjacent to the outer 90 face of the wall, as seen in Figs. 1 and 4 of the drawings, to form square loops to be engaged by the hangers. In Figs. 2 and 3 the hangers are directly fastened to the wall by means of wedges 2, let between the ends of 95 the face-bricks, and the hangers then secured by nails through their upturned inner ends, as shown. The facing material is designated by B and consists of blocks or plates made of molded or made material of such size as may be 100

fixed upon and of any substance suitable for the purpose. They may be oblong or square and have made in their upper and lower edges grooves 3, wherein is deposited a proper cementitious binder 4 to bind the blocks together and in which the reversed ends of the hangers are set, as shown in Figs. 4 and 11. In Fig. 5 of the drawings is illustrated a form of hanger adapted for use in instances where the stirrups or staples are required. This form of a metal plate 5 is provided with a nail-hole 6, through which a fastening-nail may be driven to secure the plate to the surface. The upper end of the plate is turned down at right angles to the body, as at 7, which serves to engage in the loop of the stirrups or to act as a spacing element between the wall and the inner face of the tiling. At the lower end the plate 5 is turned up at right angles to the body, as at 8, and slit at its outer portion and the slit parts turned vertically in reverse directions, as seen in the drawings at 9 10, to form locking-flanges which engage in the grooves of the tilings and are set in the cement filled therein, substantially as seen in Fig. 4 of the drawings. To one side of the extension 8 is made a downwardly-extending part 11, having its end turned up at right angles to the body of the extension to serve as a spacing medium and brace for the tiling or facing.

In instances of attachment illustrated in Fig. 3 of the drawings the body of the plate or hanger is disposed in horizontal direction and is extended in length, as seen in Fig. 6 of the drawings, and has its end turned up at right angles, as at 12, and provided with a nail-hole 6, through which the fastening-nail may be projected into the wall.

In Fig. 7 I have illustrated the manner of fastening the tiles to a weather-board surface, using the hanger illustrated in Fig. 5, and in Fig. 8 the same character of bracket is used to secure the tiling to studding direct. In Fig. 9 the similar arrangement of hangers is adapted for securing the faces to the opposite faces of the studding, thus making oppositely-faced walls, and in Fig. 10 is illustrated an instance wherein the space between the walls is utilized for conveying heat, and as a protection the inner faces of the studding are lined with vertically-arranged tiling, substantially as shown.

It will be seen from the foregoing description, taken in connection with the drawings, that the hangers which hold the facing construction in position engage in the alining grooves and that when the cement is filled in

the grooves it forms a continuous tongue, extending above and below the contiguous lines 60 of the tiling, and thus gives additional strength and stability to the vertical alinement of the tile or veneering construction.

It will be stated that hangers made for the damp-proofing should be made of large and 65 extended superficial area, so as to cover as large a wall-space as may be desired.

General directions as to different applications and kinds of work to which the improvements may be utilized may be stated: First, 70 when fixing the veneering against studding which are crooked I cut notches or seats at the required spaces apart in vertical succession, being careful to have the faces of the seats in accurate alinement, so as to preserve true verticality of the tiling; second, in utilizing the improvements for base-boards I run a board the thickness of the projection desired around the apartment and veneer against the board. 75

Having thus described my invention, what 80 I claim is—

1. The combination with a supporting-wall and a facing-wall composed of fitted forms having grooves in their meeting edges, of supporting and spacing brackets consisting of 85 plates secured to the supporting-wall and having their upper and lower ends turned at right angles to the body of the plates, and having an intermediate extension formed with a T-shaped end to engage in the grooves of the 90 forms.

2. In a building construction, a supporting-surface, a tiling-facing composed of forms having grooves in their upper and lower edges, spacing and supporting brackets at the base 95 of the facing-wall consisting of a body adapted to be secured to the supporting-surface and having its upper end turned down to form a spacing-flange and its lower end turned at right angles and its end turned vertically to 100 set in the lower groove of the facing-wall, spacing and supporting brackets having their upper and lower ends turned inward in alinement to form spacing-flanges and an intermediate extension having a T-shaped end to engage in the grooves of the tile-blocks, and a cementitious binder in the grooves to hold the blocks in alinement and lock the T ends in 105 position.

In testimony whereof I affix my signature in 110 presence of two witnesses.

CHARLES ROANE ELLIOTT.
